ICE CREAM MAKER TOY

Terry L. Bernard, 226 E. Crest, Reading, Ohio 45215

Filed Nov. 2, 1966, Ser. No. 4,520

Term of patent 14 years

(Cl. D34—15)

Fig. 1

FIG. 5

I claim:

The ornamental design for an ice cream maker toy, substantially as shown and described.
